UNITED STATES PATENT OFFICE.

LOUIS H. WELLENSIEK, OF HOUSTON, TEXAS.

DRILLING WELLS.

Application filed June 1, 1923. Serial No. 642,733.

This invention relates to improvements in earth boring and has special reference to a new and improved system of drilling wells that is particularly adapted for use in penetrating strata in which either high gas pressures or shifting formations or both are encountered.

One of the principal difficulties met with in drilling wells, especially in the case of oil and gas wells, is the presence of high gas pressure which frequently becomes so great as to blow the drilling structure out of the bore of the well. Another impediment to the drilling operation often encountered is the presence of shifting formations which tend to cave in about the drilling apparatus and stop the drilling.

The primary object of the present invention is to overcome these difficulties and to provide a drilling system in which drilling may be conducted regardless of high gas pressures or shifting formations. The invention contemplates a method of drilling in which the drill stem and an outer protective casing are simultaneously rotated while fluid is forced under pressure about the exterior of the protective casing thus tending to hold back the shifting formations and preventing them from packing in about the protective casing. The presence of the fluid under pressure about the outer casing also serves to hold back the gas and prevent it from being exerted to the detriment of the drilling operation.

For the purpose of giving a detailed description of the invention reference will now be had to the accompanying drawings illustrating hydraulic rotary drilling apparatus wherein:

Figure 1 is an elevation partially in section of an apparatus constructed in accordance with the invention and constituting an embodiment thereof.

Figure 2 is a preferred form of apparatus which may be employed.

Figure 3 is a plan view of same.

Figure 4 is an elevation partially in section drawn to a larger scale than Figure 2 and showing the mechanism attached to the outer or protective casing for rotating and handling same.

Figure 5 is a section taken on the line 5—5 of Figure 4.

Figure 6 is a detailed elevation showing

the top of an auxiliary derrick and illustrating the rotary for the drill stem.

Figure 7 is a sectional view of a casing head employed.

Figure 8 is a section taken on the line 8—8 of Figure 7.

Referring now particularly to Figure 1 it will be seen that a drill stem 10 provided with a drill 11, which preferably includes underreaming blades 12, is positioned within a depth casing or outer protective casing 13. The depth casing 13 is positioned within a casing 14 which constitutes the surface casing and which extends usually only a comparatively short distance within the well, for example, to cap rock or to some point above the strata of shifting formation or area of high gas pressure which it is desired to penetrate.

A pipe 15 communicates with the surface casing 14, or with a collar attached thereto as will be more fully described hereinafter, and serves to supply fluid under pressure to the surface casing. The fluid, which is usually water, may be supplied by means of a pump 16 or by other suitable source.

In the example of the invention thus illustrated in Figure 1 the protective casing 13 and drill stem 10 are arranged to be operated by the same means. Thus the casing 13 is attached to a rotary table 17 which may be driven by means of a pinion 18 and bevel gear 19. The rotary movement imparted to the casing 13 by the rotary 17 is transmitted to the drill stem 10 by means of a swivel swedge casing 20 which is mounted upon the upper joint of the casing 13 and adapted to hold the drill stem 10 in fixed position in regard to the casing 13 so that both the inner and outer strings of pipe may be rotated simultaneously by the same means. The casing 20 may be provided with suitable pipe gripping means (not shown) adapted to grip the drill stem 10. The pipe gripping means may, for example, be similar to those shown in my Patent 1,517,880 dated December 2, 1924, or other suitable means may be provided for accomplishing the desired result, the particular method mentioned being simply illustrative of one manner of connecting the pipes. The member 20 is preferably equipped with one or more connections 21 adapted to be connected to a flexible hose for the influx or outflow of fluid

employed in the hydraulic drilling operation. In drilling a well the drill stem 10 and protective casing 13 are simultaneously rotated while fluid is introduced into the 5 drill stem. The fluid operates to wash away the cuttings from the drill bit after which it passes upwardly through the casing 13 and is discharged through the outlet 21. If desired, the reverse return method of drilling 10 may be employed in which case the fluid is introduced through the connection 21 into the casing 13 and is returned to the surface through the drill stem 10.

Although the apparatus thus illustrated 15 in Figure 1 is well adapted for carrying out the present invention I prefer to employ in the practice of my invention drilling apparatus of such type, for example, as that shown and described in my U. S. Letters 20 Patent #1,448,172 which contemplates an apparatus of such nature that joints of pipe may be attached to the outer casing while it is in motion thereby avoiding the necessity of any stoppage of the rotation of that 25 casing during the drilling operation. Apparatus of this type is shown in Figures 2 to 6 inclusive reference to which will now be had for the purpose of setting forth in detail the method of carrying out the present invention when employing this general 30 type of mechanism.

In the apparatus thus illustrated there is a derrick 22 which may be of the usual form and construction commonly used in drilling 35 wells. An auxiliary derrick 23 is also provided being arranged within the derrick 22 and of less height than the outer derrick. The auxiliary derrick is preferably constructed of such height that it may conveniently be used in handling joints or sections of pipe of customary length.

The depth casing 13 is rotated by means of a rotary 24 which is mounted on the floor 45 of the derrick and is operated in any suitable manner, as by means of a bevel gear 25 carried on a shaft 26. The rotary 24 includes a platform 27 which is of such diameter that it will accommodate the men employed in attaching new joints to the depth 50 casing. Gripping mechanism 28 adapted to hold the casing 13 in operative connection with the rotary is mounted thereon.

The depth casing 13 is provided with a 55 swivel mechanism such as the swivel casing 29 which is supported by means of cables 30 carried on crown blocks 31 positioned in the upper part of the auxiliary derrick. In the arrangement illustrated each cable 30 carries a traveling block 32 to which an extension 60 33 of the swivel casing 29 is connected by means of pivotally mounted suspension arms 33'. The casing 29 constitutes a housing for bearing plates 34 and 35 and bearings 36, and is attached to the pipe 13, as 65 by means of the wedge slips 37.

A hopper member 38 adapted to receive fluid discharged from the depth casing 13 is suitably mounted about the upper end thereof, as by being supported on an annular support 39 resting on the top of the 70 swivel member 29. The hopper 38 has a central opening 40 through which the casing 13 is adapted to pass, the hopper being provided with an internal wall 41 which extends upwardly about the casing 13 for a 75 distance sufficient to give the hopper adequate capacity to accommodate the fluid received from the casing. The upper part of the wall 41 is preferably flared outwardly from the pipe 13, as is illustrated. The top 80 joint of the casing 13 is provided with a bell nipple 42 having its edge sufficiently flared to prevent any substantial amount of fluid from flowing down the pipe 13 and insuring the discharge of the fluid into the 85 hopper. An outlet pipe 43 is provided for discharging the contents of the hopper as may be desired.

The drill stem 10 is driven by a rotary 44 mounted on the top of the auxiliary derrick. The rotary is operated by any suitable mechanism, such as a shaft 45 geared to the rotary and carrying a sprocket wheel 46 by which power may be transmitted to the shaft, as by means of a chain belt 47. The belt 47 extends to a sprocket wheel 48 mounted on a shaft 49 to which power is supplied by means of a drive chain carried on the sprocket wheel 50. It will be observed that the shaft 49 also serves to supply power to a drum 51 by means of chain belts 52 and sprocket wheels 53 and 54. The drum 51 carries a cable 55 which extends to a crown block located at the top of the derrick 22 (not shown), the crown block carrying a cable 56 by which the drill stem 10 is supported. The drill stem is provided with a swivel 57 which may be of conventional type and provided with a hose 58 for supplying water thereto for the hydraulic drilling operation. It will also be observed that the shaft 49 serves to operate a shaft 59 by means of a chain drive 60 and sprocket wheels 61 and 62. The shaft 59 carries a drum 63 which is preferably 100 formed of two equal parts each of which 105 carries a cable 64. Each cable 64 extends to one of the crown blocks 31.

As clearly shown in Figures 7 and 8 an 110 expandible collar member such as that illustrated in my Patent 1,448,172, dated March 13, 1923, is mounted upon the upper joint of the surface casing 14 and arranged to 115 permit the depth casing 13 to descend into the bore of the well and yet maintain a relatively tight closure about this casing so as to prevent leakage between the depth and 120 surface casings and prevent the pressure fluid within the surface casing from being 125 discharged to the surface of the ground. 130

The several joints of the casing 13 are commonly connected by external couplings 65 and means must be provided for permitting these couplings to descend. In the apparatus thus illustrated a collar or casinghead member 66 is shown as being supported on the upper joint of the casing 14, as by being threadedly attached thereto. The tubular member 66 is formed with one or more sections as 66^a and 66^b which flare downwardly.

A plurality of rings 68 are slidably mounted within the tubular member 66 and are adapted to form a closure between the wall of the casinghead 66 and pipe 13. Preferably there are one or more rings 68 mounted within each flaring section as, 66^a and 66^b. As clearly shown in Figure 8 the rings 68 are formed in arcuate sections so that they may be expandable. Each arcuate section is formed with a groove 69 adapted to cooperate with one of a plurality of ribs or lugs 70 formed on the inner walls of the flaring sections 66^a and 66^b. A number of springs or resilient members 71 are suitably mounted in the members 66 to exert pressure against the underside of the several lugs 70. Set screws 73 may be provided for regulating the tension of the resilient members 71. The upper surface of the arcuate rings 68 is preferably chamfered or beveled to form a suitable surface 74 adapted to be engaged by the collars 65. The rings 68 may be equipped with packing rings 76.

As the casing 13 descends in the bore of the well during the drilling operation the collars 65 engage successively the several surfaces 74. The pressure thus exerted against the rings 68 operates to move them downwardly against the tension of the resilient members 71. It is apparent that by reason of the flared portions, as 66^a and 66^b, encountered by the rings in their downward travel, the rings will be expanded so as to permit the collars to pass through. The tension on the resilient members 71 operates to force the rings 68 upward after each collar has passed.

The tubular member 66 is shown as being equipped with a port or opening at 77 in communication with the pipe 15 by which the pressure fluid is supplied to the surface casing 14.

If desired, a stuffing box may be mounted upon the tubular member 66 in order to prevent the leakage of any fluid that may have passed through the expandable rings 68. Thus a ring 78, formed, for example, in two arcuate sections, may be positioned at the upper end of the casing head 66. This ring 78 constitutes a support for packing material 79 which is held in position by means of a gland 80, which is preferably formed in two arcuate sections. The gland is secured in any suitable manner, as by bolts 81. The stuffing box may readily be removed when

necessary to allow the passage of the collars 65.

In the preferred manner of carrying out the invention the drill stem 10 and its protective casing 13 are kept in constant rotation during the time that the difficult strata is being penetrated. With the apparatus shown in Figure 1 the fluid used in drilling is passed downwardly through the stem 10 and returns to the surface through the depth casing 13 from which it is discharged by the hose connection 21, or if it be desired to operate by the reverse return method of drilling the fluid is admitted through the hose connection 21, passes downwardly through the depth casing 13 and returns through the drill stem 10. With the type of apparatus shown in Figures 2 and 4 the fluid is pumped through the hose 58 to the drill stem 10, returns to the surface through the depth casing 13 from which it is discharged into the hopper 38 and thus removed by the pipe 43. Concurrently with the rotation of the drill stem and protective casing water or other fluid under pressure is forced through the pipe 15 and down through the surface casing 14. The fluid passing downwardly through the surface casing in the main tends to follow the bore of the well and the result is that a film of fluid under pressure is maintained about the rotating pipe 13 which holds back gas pressure and prevents the packing of shifting deposits about the rotating pipe.

Apparatus of preferred form and construction has been illustrated and described for the purpose of showing a way in which this invention may be used but the inventive thought upon which the application is based is broader than the illustrative embodiment thereof and I therefore intend no limitations other than those imposed by the appended claims.

What I claim is:—

1. In well drilling apparatus, a casing collar formed with a plurality of flared sections, expandable rings mounted in said flared sections, resilient means tending to hold said rings in unexpanded position and means for admitting fluid to said casing collar.

2. In well drilling apparatus, a casing collar formed with a flared section, expandable rings mounted in said flared section, resilient means tending to hold said rings in unexpanded position and means for admitting fluid to said casing collar.

3. In well drilling apparatus, a casing collar formed with a plurality of flared sections, expandable rings mounted in said flared sections and means tending to hold said rings in unexpanded position.

4. In well drilling apparatus, a casing head formed with a flared section, expandable rings mounted therein and adapted to en-

gage with a tubular member within said casing head, resilient means tending to hold said rings in unexpanded position, and a stuffing box for said tubular member mounted on said casing head.

5. In well drilling apparatus, a casing head formed with a flared section, expandible rings mounted therein and adapted to engage with a tubular member within said cas-

ing head, resilient means tending to hold 10 said rings in unexpanded position, a stuffing box for said tubular member mounted on said casing head and means for admitting fluid to the casing head.

In witness whereof I have hereunto set my 15 hand this 2nd day of April, 1923.

LOUIS H. WELLENSIEK.
